UNITED STATES PATENT OFFICE.

DAVID WARREN LYNCH AND RAYMOND S. LYNCH, OF LANCASTER, PENNSYLVANIA.

DESK.

Application filed February 2, 1923. Serial No. 616,552.

To all whom it may concern:

Be it known that we, DAVID W. LYNCH and RAYMOND ST. CLAIR LYNCH, citizens of the United States, residing at Lancaster, in the county of Lancaster and State of Pennsylvania, have invented certain new and useful Improvements in Desks, of which the following is a specification.

This invention relates to a novel improvement in desks suitable for children, and also susceptible of embodiment in larger form for use by draftsmen, artists, and others where a light and portable writing or work support is desired.

To that end the invention contemplates, a simple, practical and reliable construction that may be economically manufactured and assembled, and which in use will provide a substantial and comfortable combined writing surface and seat, thereby providing in a single article of furniture the necessary requisites for comfortable writing, study, work or play.

A further object of the invention is to provide a construction that may be readily taken apart for shipment and packing, and yet which in its assembled form is especially stable and well-balanced.

With the above and other objects in view which will more readily appear as the nature of the invention is better understood, the same consists, in the novel construction, combination, and arrangement of parts hereinafter more fully described, illustrated and claimed.

A preferred and practical embodiment of the invention is shown in the accompanying drawings, in which:—

Figure 1 is a perspective view of the improved desk.

Figure 2 is a side elevation thereof.

Figure 3 is a vertical cross sectional view.

Figure 4 is a detail sectional view showing the manner in which the top may be held in adjusted position with reference to the supporting bar.

Similar reference characters designate corresponding parts throughout the several figures of the drawings.

In carrying the invention into effect, it is proposed to provide a light and substantial combined desk and seat that is readily portable and therefore particularly adaptable for children's use, and yet capable of being made large enough for use by draftsmen,

artists and the like without departing from the essential features of the invention.

Referring to the embodiment shown in the drawings, it will be observed that the device consists of a suitable frame F including the leg members 1 and 2 connected near their lower ends by a cross piece 3 while the upper portions thereof are held in assembled relation by a relatively wide and substantial yoke member 4. The upper ends of the leg members 1 and 2 preferably project above the yoke member 4 and have pivoted therebetween as indicated at 5 the apron member 6 of a desk or writing shelf 7, the same being of suitable length and width according to the character of the intended use of the device and preferably provided at its near side with a strip 8 which provides a rest or ledge for papers, pencils, or like articles.

The lower side of the yoke member 4 is preferably notched or cut away as indicated at 9, the bottom wall of the notch being inclined as indicated at 10 to facilitate the reception of a supporting bar 11, the lower end 12 of which is designed to rest upon the floor or other surface, thereby providing one of the supporting feet for the device, while the upper end 13 thereof constitutes an abutment or rest for the underside of the top 7, for normally supporting the latter in position for use as a desk.

As will be seen from Figure 3 the portion of the bar 11 which fits within the notch 9 is preferably provided with a socket 14 for receiving a relatively stout screw 15 which penetrates the yoke member 4 and serves to rigidly and firmly hold the bar 11 in position without twisting, rocking or canting thereby providing an especially rigid interlocking connection between the bar and the yoke member. That is to say the bar 11 has a tight or snug fit in the notch 9, and one side edge thereof bears firmly against the inclined bottom 10 of the notch so as to insure that the bar 11 and frame F are assembled in properly inclined relation, thereby providing adequate support and stability for the desk top, and also providing adequate support for the seat member S carried by the bar.

In connection with the seat member S it will be observed that the same is preferably provided with a notched or bifurcated front portion which provides the fingers 16 for

straddling the bar 11, and the said fingers 16 are provided with openings 17 for registering with the openings 18 of the bar 11, thereby to receive a locking pin 19 for holding the seat in position. As will be seen from Figure 3, the portion of the seat between the fingers 16 is preferably beveled as indicated at 20 to enable the seat to engage the upper edge of the bar 11 in such a manner that the seat will be held in horizontal position, and by providing the series of adjustment openings 18 in the bar 11, it will be apparent that the seat S may be placed in any one of a number of positions to adjust the same properly with reference to the top or writing shelf 7.

If desired, the underside of the top 7 may be provided with any suitable adjusting means such for example as the link 21, the same being pivotally carried as at 22 by the underside of the top 7 and having the slot 23 engaging over a stud 24 and adapted to be clamped in position by the wing nut 25. This arrangement permits of the top 7 being adjusted to the desired incline, and may be especially useful to artists or draftsmen since it provides in effect an easel upon which the work may be supported.

From the foregoing it will be apparent that the present invention provides in effect a tripod support, one of the members of which adjustably carries the seat S while the others pivotally carry the top 7. Also, it will be apparent that the device is made in such a way that it may be readily taken apart, or knocked down to facilitate its transportation, shipment, or storage. That is to say by simply removing the fastening screw 15 the frame F and bar 11 may be separated, and by removing the pin 19 the seat may be detached from the bar, whereupon the top or writing shelf 7 may be

folded toward the frame F and all of the parts assembled in comparatively compact relation.

Without further description it is thought that the features and advantages of the invention will be readily apparent to those skilled in the art and it will of course be understood that changes in the form, proportion and other details of construction may be resorted to without departing from the spirit of the invention or scope of the appended claims.

We claim:—

1. A desk of the class described, including in combination, a supporting frame having a transverse yoke member at its upper end, said yoke member being provided with a notch at its bottom edge, a desk top pivotally carried by the upper end of the frame, a supporting bar fitting into said notch and extending upwardly to provide a rest for said top and its lower end providing a supporting foot, means for securing the bar in said notch, a seat carried by the intermediate portion of the bar, and means for adjusting the top member with reference to the upper end of the bar.

2. A desk of the class described including a frame having supporting feet, a top member pivoted to the upper end of said frame, an intermediate yoke member, and a supporting bar having its intermediate portion interlocked with said yoke member and the opposite ends thereof respectively constituting an abutment upon which the pivoted top may rest and a supporting foot, and a seat carried by the supporting bar.

In testimony whereof we hereunto affix our signatures.

DAVID WARREN LYNCH.
RAYMOND S. LYNCH.
